PANEL ELECTRONIC METER FOR SWITCH-BOARDS OR THE LIKE

Takesi Gomi, Tokyo, Japan, assignor to Yokogawa Electric Works, Limited, Tokyo, Japan

Filed Dec. 19, 1960, Ser. No. 63,290

Term of patent 14 years

Claims priority, application Japan July 2, 1960

(Cl. D52—6)

FIG. 1

FIG. 2

FIG. 3

FIG. 4

FIG. 5

FIG. 6

FIG. 1 is a front elevational view of a panel electronic meter for switchboards or the like, showing my new design;

FIG. 2 is a top plan view;

FIG. 3 is a plan view as seen from the bottom;

FIG. 4 is a side elevation as seen from the left side of FIG. 1;

FIG. 5 is a rear elevational view thereof; and

FIG. 6 is a detail of the lower right corner according to my design.

I claim:

The ornamental design for a panel electronic meter for switchboards or the like, substantially as shown.
